US00D691845S

(12) **United States Design Patent**
Tosdale et al.

(10) **Patent No.:** **US D691,845 S**
(45) **Date of Patent:** **** Oct. 22, 2013**

(54) **FOOD PAN**

(71) Applicant: **The Vollrath Company, L.L.C.**,
Sheboygan, WI (US)

(72) Inventors: **David R. Tosdale**, Manitowoc, WI (US);
Theresa M. Mayer, Sheboygan, WI
(US)

(73) Assignee: **The Vollrath Company, L.L.C.**,
Sheboygan, WI (US)

(**) Term: **14 Years**

(21) Appl. No.: **29/444,969**

(22) Filed: **Feb. 6, 2013**

Related U.S. Application Data

(60) Continuation of application No. 29/429,473, filed on Aug. 10, 2012, now Pat. No. Des. 677,972, which is a continuation of application No. 29/366,399, filed on Jul. 23, 2010, now Pat. No. Des. 665,221, which is a division of application No. 29/345,670, filed on Oct. 20, 2009, now Pat. No. Des. 620,306, which is a continuation-in-part of application No. 29/340,791, filed on Jul. 24, 2009, now Pat. No. Des. 613,108, which is a division of application No. 29/324,933, filed on Sep. 23, 2008, now Pat. No. Des. 597,371.

(57) **CLAIM**

We claim the ornamental design for a food pan, as shown and described.

DESCRIPTION

FIG. 1 is a front perspective view from above of the claimed design;

FIG. 2 is a front view of the claimed design;

FIG. 3 is a right side view of the claimed design;

FIG. 4 is a rear view of the claimed design;

FIG. 5 is a left side view of the claimed design;

FIG. 6 is a bottom view of the claimed design; and,

FIG. 7 is a top view of the claimed design.

The broken lines in the drawings are for illustrative purposes only and form no part of the claimed design.

1 Claim, 7 Drawing Sheets
